Patented Mar. 31, 1964

197,873

MOBILE ROOM STERILIZER

William Few and George W. Newton, Durham, N.C., assignors to Newton Instrument Company, Durham,
N.C., a corporation of North Carolina

Filed Apr. 2, 1962, Ser. No. 69,517

Term of patent 7 years

(Cl. D83—1)

FIG. 1

FIG. 3

FIG. 1 is a perspective view of a mobile room sterilizer showing our new design;

FIG. 2 is a perspective view thereof as seen from the opposite side of FIG. 1; and

We claim:

The ornamental design for a mobile room sterilizer, substantially as shown.
